UNITED STATES PATENT OFFICE.

WILLIAM L. HUDSON, OF SILER CITY, NORTH CAROLINA, ASSIGNOR TO ALLEN MORRISON SIGN COMPANY, INCORPORATED, OF LYNCHBURG, VIRGINIA.

WIND-MOTOR SIGN.

Application filed May 27, 1921. Serial No. 472,987.

To all whom it may concern:

Be it known that I, WILLIAM L. HUDSON, a citizen of the United States, residing at Siler City, in the county of Chatham and 5 State of North Carolina, have invented certain new and useful Improvements in a Wind-Motor Sign, of which the following is a specification.

This invention relates to a wind motor 10 sign and has for its principal object to provide a simple, durable and efficient sign which may be placed along the highway having means combined therewith for attracting the attention of travelers thereto.

15 Another object of the invention is to provide a wind direction indicator having a tail or vane upon which may be placed advertising matter, said vane being easily detached from and attached to the sign proper.

20 The invention consists in the novel parts, constructions, combinations and instrumentalities and improvements herein shown and described.

In the drawing:—

25 Figure 1 is an elevational view of the device,

Figure 2 is a top plan view thereof, and

Figure 3 is an edge elevational view thereof.

30 Referring to the drawing in detail it will be seen that 1 designates the post or other support in the top of which is supported a rod 2 which extends in vertical alignment with the post 1. The sign board proper 3

35 consists of two parallel spaced panels 4 between which is situated a sleeve 5 for receiving the upper end of the rod 2 and the upper end of this sleeve is closed by means of a threaded cap 6. In alignment with the

40 sleeve 5 and at the bottom edge of the panels 4 there is situated a member 7 for receiving the rod 2. From this construction it will be seen that the sign is swivelly mounted upon the rod 2. At one end of the sign proper 45 between the panels 4 there is situated a beam 9 and a similar beam 10 is situated so as to be parallel and spaced therefrom and these two beams 9 and 10 are connected at their ends by rods 10 thus forming a frame in

50 which is rotatably situated a wind wheel indicated generally by the numeral 12. This wind wheel is suitably mounted on a stub axle 13 carried in the journals 14 fixed to the beams 9 and upon this stub axle 13 there 55 is mounted a hub structure 15 radiating

from which are disposed the spokes 16 having at their ends the wind blades 17.

It is to be noted that the top and bottom of the wind wheel frame constituted by the bars 9 and 10, extend above and below the top 60 and bottom of the sign board 4. The wind wheel likewise extends above and below the top and bottom of the sign board 4, but I do not limit myself to this arrangement inasmuch as a small wheel or wheels may be 65 provided if found desirable.

At the other end of the sign proper there is situated a bar 19 between the panels 4 and a similar bar 20 is detachably engaged therewith by means of bolts and nuts 21. 70 A tail or vane 23 is fixed to the bar 20 so as to extend in alignment with the sign board proper and this vane will point in the direction in which the wind is blowing as will be evident. This vane 23 is constructed so that advertising matter may be placed thereon and of course similar advertising matter may also be placed upon the panels 4. The advantage in having the vane 23 detachable is that these advertising matters may 80 be easily placed thereon when the vane is detached as it will be readily recognized as a very difficult task to paint signs or otherwise place signs upon the vane 23 while in its attached position.

85 The vane 23 is made narrower than the sign board proper so as to provide a well balanced sign and one which has an odd appearance and therefore one which will attract considerable attention. The oddity of the sign is increased by extending the wind wheel frame above and below the sign board as explained hereinbefore, together with the fact that the vane 23 is made narrower than the sign board proper.

90 It will further be noted that the various parts of this wind motor sign may be easily assembled and disassembled for shipping purposes and so that various parts thereof may be repaired or replaced when found necessary.

95 From the foregoing description, taken in connection with the accompanying drawings, the construction and operation of the device will be readily understood without 100 a more extended explanation. As numerous changes in form, proportion, and in the minor details of construction may be resorted to without departing from the spirit of this invention, I do not wish to be limited 110

2
to the construction herein shown and described other than as claimed.

Having thus described my invention what I claim as new is:—

- 5 1. An advertising device in combination, a sign revolvably mounted, an attention attracting device situated at one end of the sign, a bar detachably mounted at the other end of the sign and a vane attached to the bar.
- 10 2. An advertising device in combination, a support, a rod extending from the support, a sign including a pair of spaced panels, a sleeve situated between the panels, a cap mounted on the sleeve, said rod extending into the sleeve so as to revolvably mount the sign thereon, an attention attracting device mounted at one end of the sign, and a vane mounted at the other end of the sign.
- 15 3. An advertising device in combination, a support, a sign revolvably mounted on the support, a beam situated at one end of the sign, a similar beam spaced from the first beam, rods connecting the beams at their ends, an attention attracting device mounted between the beams and a vane attached to the other end of the sign.
- 20 4. An advertising device in combination, a support, a sign revolvably mounted on the support, a bar situated at one end of the sign, a similar bar detachably mounted on the first bar, and an advertising device supported by the second bar.
- 25 5. An advertising device comprising a

relatively wide rotatable sign board, a frame 35 mounted at one end of the board, a rotatable member mounted in the frame, and a relatively narrow vane mounted on the other end of the sign board.

6. An advertising device comprising a 40 sign board, a beam situated at one end thereof, a second beam spaced from the first beam, spacing elements connecting the beams to retain them in spaced relation, and a member rotatably mounted between the beams. 45

7. An advertising device comprising a rotatable sign board, a wind wheel frame mounted at one end of the board and supported solely thereby, a rotatable member mounted in the frame, and a vane mounted 50 on the other end of the sign.

8. An advertising device comprising a rotatable sign board, a frame mounted at one end of the board and extending above and below the board, a rotatable member mounted in the frame, and a vane mounted on the other end of the sign board. 55

9. An advertising device comprising a relatively wide rotatable sign board, an attention attracting device mounted at one end 60 of the board and a relatively narrow vane mounted on the other end of the sign board.

In testimony whereof I affix my signature in presence of two witnesses.

WILLIAM L. HUDSON.
